UNITED STATES PATENT OFFICE.

FRANKLIN E. ARNDT, OF GALION, OHIO, ASSIGNOR TO THE GALION IRON WORKS & MFG. CO., OF GALION, OHIO, A CORPORATION OF OHIO.

REVOLVING SAND-SCREEN.

1,231,113.

Specification of Letters Patent. Patented June 26, 1917.

Application filed March 2, 1917. Serial No. 152,125.

To all whom it may concern:

Be it known that I, FRANKLIN E. ARNDT, a citizen of the United States, residing at Galion, in the county of Crawford and 5 State of Ohio, have invented certain new and useful improvements in Revolving Sand-Screens, of which the following is a specification.

This invention comprehends certain new 10 and useful improvements in gravel screens or graders, and relates particularly to an improved construction of sand screen.

The invention has for its primary object a practical, durable and very efficient construction of device of this character, in 15 which the screen is made in two semi-cylindrical sections bolted together, to form the complete cylinder that surrounds the perforated shell or drum of the grading device, each mat or section embodying a plurality of wire rods secured rigidly in spaced 20 relation to each other and all of the parts being capable of being easily and cheaply manufactured and easily assembled or 25 put up.

A further object of the invention is to provide a revolving sand screen, the parts of which are light and yet strong, and well capable of withstanding the hard use to 30 which a device of this kind is necessarily subjected in service.

And the invention also aims to generally improve devices of this class so as to render them more useful and commercially desirable.

With these and other objects in view, as will more fully appear as the description proceeds, the invention consists in certain constructions, combinations and arrangements of the parts that I shall hereinafter 40 more fully describe and claim.

For a full understanding of the invention, reference is to be had to the following description and accompanying drawings, 45 in which

Figure 1 is a partial section and partial side elevation of a portion of a rotary grader embodying the improved sand screen of my invention.

Fig. 2 is a detail view of the end bars for 50 the two mats or sections of the screen.

Figs. 3 and 4 are detail views illustrating the manner in which the spacing bars are held in place at their ends.

Fig. 5 is an end view of the screen, the 55 perforated drum or shell being shown in section,

Fig. 6 is a side view of a portion of one of the spacing bars hereinbefore mentioned,

Fig. 7 is an edge view thereof, and 60

Fig. 8 is a fragmentary plan view of the end bars used to hold the ends of the screen wires and to secure one section or mat to the other through the instrumentality of bolts or similar fastening devices. 65

Corresponding and like parts are referred to in the following description and designated in all of the views of the accompanying drawings by like reference characters.

Referring to the drawings, the numeral 1 designates a perforated drum or shell of a sand and gravel grader embodying the improvements of my invention, said drum being mounted to rotate in any desired way 70 and at any desired or predetermined angle according to the circumstances of the case, said drum in the present instance being shown as secured to spiders 2 upon a shaft 3 that is journaled in bearings 4 upon standards 5. Only one spider, bearing, and standard is shown, but it is to be understood that two are provided, one at each end of the apparatus and that the drum and its surrounding and concentrically arranged sand screen 75 may be revolvably supported in any other desired way. 80

My improved sand screen consists of two semi-cylindrical mats or sections, each comprising any desired number of curved or 90 bowed wires or rods 6 which pass through openings 7 in spacing bars 8, there being any desired number of bars, preferably arranged at regular intervals or at equal distances apart. The ends of the spacing bars 95 7 are curled upon themselves, as best illustrated in Fig. 7, to form eyes or loops 9 through which the bolts 10 pass, said bolts

also passing through rings or bands 11 at the two sides or ends of the screen and being secured thereto by means of the nuts 12.

The ends of the wires or rods 6 extend 5 through openings 13 that are formed in the end bars 14, the bars 14 being angle bars, as best illustrated in Fig. 2 and being secured together in abutting relation by any desired number of bolts or similar fastening devices 15, and after the ends of the wires or rods 6 are passed through the openings 13, they are hooked or bent back upon themselves, as shown at 6' in Fig. 2 and thus securely held in place. The ends of the angle bars 14 overlap the semi-circular bands 11 and are secured thereto by bolts 16 as best illustrated in Fig. 8.

The complete screen is secured to the drum 1 outside of and in concentric relation thereto by means of any desired number of bolts 17 and spacing pipes or sleeves 18, as clearly illustrated in Fig. 5.

From the foregoing description in connection with the accompanying drawings, the 25 operation of my improved sand screen will be apparent to those familiar with the art to which this invention appertains. The apparatus is tilted and held at the desired inclination in any desired way, and the sandy 30 gravel, from the pit, for example, is dumped into the screened end of the drum which, with its surrounding sand screen, is rotated at any desired rate of speed and by any desired power. If the screen were not provided, it is evident that quite a number of 35 relatively large stones or pebbles would be thrown by the centrifugal action out through the frame and find their way into the sand bin, but this is prevented by the screen, and 40 such particles are caused to remain within the device until they are finally tumbled out into the gravel bin at one end of the screen.

It will be seen that I have provided a 45 very practical, durable and efficient construction of sand screen, the parts of which may be very easily manufactured and assembled. The wire rods 6 may be very readily passed through the openings 7 in the spacing bars 8 and the latter firmly secured at their ends to the semi-circular bands 11 by the bolts 10 passing through the openings formed for them in said bands, and the two semi-cylindrical sections or mats, may be very easily secured together by passing 50 the bolts 15 through registering openings formed for them in the outwardly projecting flanges of the angle bars 14 to form the complete screen.

While the accompanying drawings illustrate 55 what I believe to be the preferred embodiment of my invention, it is to be understood that the invention is not limited thereto, but that various changes may be made in

the construction, arrangements and proportions of the parts without departing from 65 the scope of the invention as claimed.

What is claimed, is:

1. A sand screen comprising sections, each of which includes a plurality of bowed rods, angle bars formed in one flange with openings in which the ends of said rods are hooked, the angle bars of one section abutting against the angle bars of the adjoining section, fastening devices extending through the abutting flanges of said bars to 75 secure the sections together, bands, said angle bars overlapping said bands, and fastening devices extending through said bands and the overlapping ends of said bars.

2. A sand screen, comprising sections, each of which includes a plurality of bowed rods and angle bars formed in one flange with openings in which the ends of said rods are engaged, the end bars of one section abutting against the end bars of the other section, and fastening devices extending through the abutting flanges of said end bars to 85 secure the sections together.

3. A sand screen, including a plurality of bowed rods, a plurality of spacing bars formed with openings through which the rods extend, bands at the ends of said spacing bars, the latter having their ends coiled upon themselves to form eyes, bolts passing 90 through said eyes and the bands and securing the bars to the bands, and end bars to 95 which the ends of said rods are secured.

4. A sand screen, including a plurality of bowed rods, a plurality of spacing bars formed with openings through which the rods extend, bands at the ends of said spacing bars, the latter having their ends coiled upon themselves to form eyes, bolts extending 100 through said eyes and the bands and securing the bars to the bands, end bars to 105 which the ends of said rods are secured, and bolts securing the ends of the end bars to said bands.

5. In a machine of the character described, the combination with a perforated drum, of 110 a sand screen surrounding said drum and spaced therefrom in concentric relation thereto, said screen comprising two semi-cylindrical sections, each of which comprises a plurality of bowed rods, spacing bars 115 formed with openings through which the rods extend, bands, bolts passing through said bands, the bars having their ends coiled around said bolts, angle bars formed with openings in which the ends of said rods are 120 hooked, said angle bars at their ends overlapping and resting upon said bands, bolts extending through the bands and the overlapping ends of the angle bars so as to secure 125 said bars to the bands, bolts securing the angle bars of one section to the angle bars

of the other section, and means for holding the screen in spaced relation to the drum.

6. A sand screen including a plurality of bowed rods, end bars to which the ends of said rods are connected, bands, transversely extending means secured to said rods intermediate of the ends of the latter and holding said rods in spaced relation to each other, fastening devices securing the ends of the

spacing means to the bands and fastening 10 devices securing the ends of the end bars to the bands.

In testimony whereof I affix my signature in the presence of two witnesses.

FRANKLIN E. ARNDT.
